(57) **CLAIM**

The ornamental design for a display screen with a user interface, as shown and described.

DESCRIPTION

FIG. 1 is a front view of a display screen with a user interface showing our new design; and,

FIG. 2 is a front view of an alternate embodiment of a display screen with a user interface showing our new design.

The broken line showing of the display screen is for environmental purposes only and forms no part of the claimed design.

1 Claim, 2 Drawing Sheets

FIG. 1

FIG. 2
